ANDY MAGYAR, OF HUTCHINSON, KANSAS.

BED-BOTTOM.

1,158,254.

Specification of Letters Patent. Patented Oct. 26, 1915.

Application filed June 24, 1914. Serial No. 847,072.

To all whom it may concern:

Be it known that I, ANDY MAGYAR, a subject of the King of Hungary, residing at Hutchinson, in the county of Reno and State 5 of Kansas, have invented certain new and useful Improvements in Bed-Bottoms, of which the following is a specification, reference being had therein to the accompanying drawing.

10 This invention relates to bed bottoms, and has for its object to provide a bed bottom of the spring type combined with means for resiliently supporting the ends of the bed bottom whereby a cushioning effect is set 15 up when a bed in which the bottom is employed is occupied.

Further objects of the invention are to provide a resiliently supported bed bottom of the spring type, which is simple in its 20 construction and arrangement, readily set up with respect to the foot and head pieces of the bed, strong, durable, affording a resilient support for the occupant of the bed and inexpensive.

25 With the foregoing and other objects in view, the invention consists of the novel construction, combination and arrangement of parts as hereinafter more specifically described and illustrated in the accompanying 30 drawings, wherein is shown an embodiment of the invention, but it is to be understood that changes, variations and modifications can be resorted to which come within the scope of the claim hereunto appended.

35 In the drawings wherein like reference characters denote corresponding parts throughout the several views:—

Figure 1 is a side elevation illustrating a resiliently supported spring bed bottom in 40 accordance with this invention, Fig. 2 is a top plan view of the bed illustrating the adaptation therewith of a bed bottom in accordance with this invention. Fig. 3 is a detail view of a section of the post with its 45 slot and keeper.

Referring to the drawings in detail, 1 denotes the head piece of a bed which head piece includes a pair of posts 2, 3. The foot piece of the bed is indicated by the reference character 4 which foot-piece includes a pair of posts 5, 6. Each of the posts of the foot and head pieces 1, 4, is provided with a bayonet slot 7 in the inner face of the post, the slot being disposed to provide 55 one leg thereof vertically and the other transversely of the post. Each of the posts

of the foot and head pieces 1, 4 is hollow and arranged therein is a vertically disposed coiled spring 8, which is of less length than the vertical leg of the slot 7. The spring 60 8 is supported at its bottom in any suitable manner within the post and provides resilient supports for the bed bottom to be presently referred to. The horizontal leg of the slot 7 provides means to permit of the ends 65 of the bed bottom extending into the post.

Secured to the inner face of each of the posts of the head and foot pieces 1 and 4 by the holdfast devices 9 is a vertically disposed retaining member 10, which has its 70 lower end formed with a right angularly disposed lug 11, which extends into the horizontal leg of the slot 7, and said lugs 11 constitute means to prevent the ends of the bed bottom slipping out of the slots 7. 75

The head and foot pieces are connected together by side rails 12 in the known manner and each of the posts of the head and foot pieces is provided with casters 13. The bed bottom is formed from a frame consisting 80 of a pair of tubular side bars 14 and 15, and a pair of angle-iron end bars 16 and 17. The side bars 14 and 15 extend through the vertical flanges of the end bars 16 and 17 and are secured by the hold-fast devices 18 85 to the horizontal flanges of said end bars 16 and 17. The extended ends of the side bars 14 and 15 indicated at 19, project into the slot 7 and are seated upon the tops of the springs 8 whereby the frame is resiliently 90 supported.

Extending transversely of the frame of the bed bottom, centrally of said frame and above and below the same are flat plates 20 and 21 the length of said plates being less than the width of the frame. Interposed between said plates 20 and 21, as well as being connected thereto, is a series of vertically disposed coiled springs 22. The plate 21 is connected to the horizontal flanges of the end bars 16 and 17, by oppositely disposed elongated coiled springs 23 and each of said springs extending from an end bar inwardly and downwardly at an inclination. Connected to the upper edge of the vertical flanges of the end bars 16 and 17 is a series of inwardly projecting coiled springs 24, which series is connected to a metallic latticed body 25, and the latter is coupled with the plate 20 by links 26. 95 100 105 110

Projecting inwardly from the vertical flange of each of the end bars at each end

thereof, is an inwardly extending elongated coiled spring 26^a and the springs 26^a of one end bar are connected to the springs 26^a of the other end bar by chains 27. The chains 27 are coupled with the ends of the plate 20 by links 28.

The springs 22 maintain the plate 20 and the latticed body 25 above the frame of the bed bottom and said springs 22 form a resilient support when the bed bottom is occupied.

What I claim:—

The combination with the foot and head posts of a bed, each of said posts being hollow and having its inner face provided with an inverted L-shaped slot, and resilient supporting members within said posts, of a re-

silient bed bottom comprising a frame having side rails provided with reduced end portions, said portions extending through the vertical legs of said slots and seated upon said resilient supports whereby said bed bottom is resiliently supported, and retaining members carried by said posts and provided with lugs extending in the short horizontal legs of said L-shaped slots for maintaining the extended portions of said frame in said posts.

In testimony whereof I affix my signature in the presence of two witnesses.

ANDY MAGYAR.
